DRIVING MECHANISM FOR OSCILLATING SHAFTS

William S. Lowe, Nichols, Conn., assignor to General Electric Company, a corporation of New York

Application May 4, 1937, Serial No. 140,627

5 Claims. (Cl. 308—36.1)

The present invention relates to driving mechanisms of the type having a vertical oscillating shaft journaled in a sleeve bearing. One use of such mechanisms is in domestic washing machines where the vertical shaft is used to drive the agitator.

The object of my invention is to provide an improved construction in driving mechanisms of this type which will prevent the pumping of oil 10 through the space between the oscillating shaft and the sleeve bearing.

In the accompanying drawings, Fig. 1 is a fragmentary elevation of a washing machine having a driving mechanism embodying my invention in section along lines 1—1 of Fig. 2; Fig. 2 is a top plan view in section along lines 2—2 of Fig. 1; Fig. 3 is a perspective view of the guide for the reciprocating rack; Fig. 4 is a sectional view taken on line 4—4 of Fig. 1; Fig. 5 is a sectional view taken on line 5—5 of Fig. 2; Fig. 6 is a diagrammatic view showing the side- 20 wise movement of the oscillating shaft in the sleeve bearing; Fig. 7 is a diagrammatic view of the lower end of the oscillating shaft illustrating the manner in which the shaft tends to 25 pump lubricant upward through the space between the shaft and the sleeve bearing; and Fig. 8 is a sectional elevation of a modification having a seal above the bearing as an additional 30 precaution against the leakage of lubricant.

Referring to the drawings, I have shown my invention applied to the driving mechanism for washing machines shown in Patent No. 2,064,653, Forstrom, December 15, 1936. In this construction the tub 1 is supported at the center by a tubular post 2 which projects through a central opening in the bottom of the tub. The tub rests on a flange 4 on the post 2 and is clamped between the flange and a nut 5 which is threaded 35 on the post. Suitable gaskets 6 are arranged between the tub and the flange 4 and the nut 5 to prevent leakage. The lower end of the post 2 is secured to the top of the gear casing 7 and is supported thereby. The gear casing 40 extends diametrically across and is bolted at either end to the depending sides of a cylindrical skirt 8. Legs 9 for supporting the washing machine are secured to the skirt 8. The gear casing braces the skirt 8 and provides a rigid 45 central support for the tub. The outer edge of the tub is tightly held against a rubber cushion 10 on the upper edge of the skirt 8. This provides additional support for the tub. The lower end of the tub projects within and is wedged 50 against the upper rim of the skirt. This in-

creases the lateral rigidity of the skirt and allows the use of lighter material for the skirt.

A vertical shaft 11 for driving an agitator 12 extends upwardly through the post and is supported by a suitable combined sleeve and thrust bearing (not shown) at the upper end of the post. The agitator has a depending tubular portion which extends downwardly around the post. A collar 13 which is secured to the agitator at the lower end guides the movement of the agitator. The lower end of the agitator shaft 11 is carried in a sleeve bearing 14 in the upper wall of the gear casing 7. A chamber 15 is provided above the bearing 14 to collect lubricant which may be carried above the bearing. This 15 lubricant is returned to the gear casing through a well or groove 15a in the top wall of the gear casing. The well has an opening 15b through which the lubricant flows. The opening is located so that it is always above the level of the 20 lubricant in the gear casing regardless of the position of the gear casing. The agitator shaft 11 extends within the gear casing 7 and has a pinion 16 keyed to the lower end which is adapted to mesh with a reciprocating rack 17 to cause 25 oscillation of the agitator. The left end of the rack is provided with a crank pin 18 which is rotatable in a bearing eccentrically located in a worm wheel 19. The worm wheel is keyed to the lower end of a vertical shaft 20 which is 30 journaled in the bearing 21 in a tubular wringer post 22. The upward thrust of the worm gear is taken by the lower edges of the bearing 21 which serves as a thrust bearing. The wringer post is clamped to the upper wall of the gear 35 casing by a split clamp 23 integral with the upper wall of the gear casing. The worm wheel 19 is rotated by a worm 24 which is driven by an electric motor 25 carried on the gear casing by rubber rings 26 clamped to supports 27. An 40 intermediate shaft 28 is connected between the motor shaft 29 and the worm shaft 30 by flexible couplings 31. A thrust ball 32 is provided at the end of the worm shaft 30. The thrust ball is adjusted by a screw plug 33. With this arrangement, the worm wheel 19 is continuously rotated in one direction by the motor, and the crank pin 18, bearing in the worm wheel, causes the rack 17 to be reciprocated. The body of the rack 17 is offset and rigid so that although the end 45 of the rack carrying the crank pin 18 is below the teeth of the worm wheel 19, the teeth of the rack and the bearing of crank pin 18 are in line with the teeth of the worm wheel 19. This 50 reduces the load on the bearings of the shaft 55

20 and eliminates vertical forces in the rack thrust which would have a tendency to cause slaps resulting in objectionable noises.

The reciprocating movement of the rack 17 is guided by a guide 34a shown in Fig. 3. The guide has flanges 34 which extend over the upper and lower sides of the rack. Secured to the lower flanges is a tongue 35 which slides in a groove on the under side of the rack and holds the rack 10 in the guide. From the rear edge of the guide extend ears 36 which are pivoted on the inner end of the plunger 37 slidably in the walls of the gear casing 7. The ears 36 support the rack on the plunger and the pivotal connection between the ears 36 and the plunger permit pivotal movement of the guide during the reciprocating movement of the rack. The outer end of the plunger 37 projects through the side wall of the gear casing, and the plunger is urged outward 15 by a spring 38 arranged between the gear casing and the outer end of the plunger. The spring 38 thereby tends to move the plunger to a position in which the rack is out of mesh with the pinion. The plunger is moved inwardly to the 20 position shown in Fig. 2 by means of a control lever 39 pivoted on a bracket 40 secured to the outside of the gear casing. The end of the control lever is provided with a cam 41 which engages a set screw 42 threaded into the end of 25 the plunger 37. When the control lever is in the position shown in full lines in Fig. 2, the rack is pressed into engagement with the pinion. When the control lever is in the position shown in dotted lines, the spring 38 moves the plunger outwardly, thereby moving the rack out of 30 engagement with the pinion.

On the under side of the crank pin 18 is a pin 42a which is pressed by a spring 43 against the cover 44 of the gear casing. The friction 40 between the pin 42a and the cover of the gear casing opposes the reciprocating movement of the rack and thereby tends to prevent overtravel of the reciprocating rack and reduces the back-lash between the worm and the worm gear. The friction between the pin 42a and the cover 45 of the gear casing also tends to retard the rotation of the crank pin and thereby tends to hold the crank pin against its bearing in the worm wheel during all parts of the reciprocating movement of the rack and particularly during the reversal of the reciprocating movement of the rack. The frictional force between the crank pin and its bearing is always in the same direction, and causes the rack to bear against the 50 back of the guide 34a, thus preventing wobbling of the rack in the guide and eliminating noise from this source. When the rack is being reciprocated, it is continuously held against the back of the guide 34a and the tongue 35 is then 55 merely a means for making sure that the rack is pulled out of mesh with the pinion in case of binding between some of the parts. The spring pin 42a also prevents the crank pin 18 falling from its bearing in the worm wheel 19. The pin 42a supports the wringer shaft 20, eliminating the need for a thrust bearing to support the 60 gravity component of the worm gear and shaft thrust. It would be inconvenient to provide such a thrust bearing at the bottom of the wringer shaft, and if the thrust bearing were provided at the top of the wringer shaft, it would be difficult to prevent excessive play between the bearing and the shaft due to expansion and contraction of the shaft and the wringer post. The 65 pin 42a also prevents vertical movement of the 70

shaft due to variations in the vertical reaction between the worm 24 and the worm wheel 19 caused by the variable load taken by the reciprocating rack. If this vertical movement were not prevented by the pin 42a it would produce a gear noise due to the change in mesh between the worm 24 and the worm wheel 19, and it would also produce a knock on the thrust bearing used to take the variable upward thrust of the worm gear. 10

When the bearing 14 is a plain sleeve bearing a considerable quantity of lubricant is forced upward through the bearing during the oscillation of the shaft 11. For this reason it has been necessary to provide a passage such as the well 15 15a in order to return this lubricant to the gear casing, otherwise, the lubricant may overflow the top of the gear casing. Since the shaft 11 is normally oscillated at the rate of about sixty 20 complete oscillations per minute, each oscillation being through an angle of the order of 180 degrees, there is no readily apparent reason why the lubricant should be forced upward through the bearing while the shaft is oscillating. The lubricant could not be forced upward through 25 the bearing because of the difference in pressure between the inside and the outside of the gear casing since these pressures are the same due to the vent 15b. Capillary action could not be wholly the cause of this leakage since the lubricant is not forced through the bearing while the shaft is stationary. It, therefore, seems clear 30 that the forcing of lubricant upward through the sleeve bearing must be due to a pumping action. During the oscillation of the shaft the 35 shaft may have four types of motion: (1) an up and down motion due to end play; (2) an oscillating motion, through an arc of the order of 40 180 degrees, the velocity and acceleration being different in each half cycle of the oscillation; (3) a tipping motion which is indicated diagrammatically in Figs. 6 and 7; and (4) a sidewise motion of the shaft in the bearing. Tests indicate that the pumping action is due mainly to causes (2), (3), and (4). The up and down 45 movement of the shaft is not present in a properly designed construction. The tipping action illustrated diagrammatically in Figs. 6 and 7 is in effect a pivotal movement of the shaft about the sleeve bearing 45 at the upper end of the 50 post 2. This action is permitted by the clearance in the sleeve bearing 14 which is greatly exaggerated in Fig. 6 and somewhat less exaggerated in Fig. 7 for the purpose of illustration. Fig. 7 shows the position of the shaft when the 55 rack is traveling to the right. In moving to this position, lubricant is sucked in at 46 and forced out at 47. When the rack reverses and moves toward the left, the lubricant which was sucked in at 46 is forced out at 48 and lubricant is 60 sucked in at 49. The tilting of the shaft, therefore, produces a pumping action which tends to force the lubricant upward through the bearing. It has been found that a sidewise motion of the 65 shaft in the bearing without any tilting will produce the same pumping action. A sidewise movement of the shaft can result from the thrust along the center-line of the reciprocating rack. It can also result from the variation in the force exerted by the teeth of the rack on the teeth 70 of the pinion. This force varies in magnitude with the angular position of the pinion and is in general perpendicular to the center-line of the rack.

The pumping action from all causes is elimi- 75

nated by providing vertical slots 50 in the bearing surface of the bearing. Two of the slots are arranged on the center-line of the reciprocating movement of the rack and the other two slots are equally spaced therebetween. These slots prevent the building up of pressure between the shaft and the bearing during the tilting or side-
 5 wise movement of the shaft and thereby prevent the pumping of the lubricant. That is, instead of being forced upward by the tilting of the shaft or the sidewise movement of the shaft toward the bearing, the lubricant is forced into the slots 50 and drains into the gear casing. The slots 50 also serve to scrape excess lubricant from the
 10 shaft and thereby prevent any pumping action due to changes in the angular velocity of the shaft. Although the slots have been illustrated in the bearings, it is obvious that these slots could also be placed in the shaft. The slots are shown
 15 as vertical and there is, therefore, no tendency for lubricant to be forced upward in the slots due to centrifugal action. The slots need not be absolutely vertical, it merely being essential that the slots have insufficient inclination to
 20 cause lubricant to be forced upward therein by centrifugal action.

In the construction shown in Fig. 8 a seal has been provided as an additional precaution to prevent leakage of lubricant. This seal is not necessary. The seal comprises a bearing and sealing washers 52 which are forced against the lower end thereof by a compression spring 53 arranged between the upper end of the bearing 14 and a washer 54. With this arrangement a
 25 space is provided between the upper end of the bearing and the seal in which lubricant can collect. Any lubricant collecting in this space will drain to the gear casing through the slots 50.

What I claim as new and desire to secure by Letters Patent of the United States, is:

40 1. In combination, a casing containing lubricant, a shaft extending through the top wall of the casing, a sleeve bearing for the shaft in the top wall of the casing, means including a reciprocating member within the casing for oscillating the shaft, and an axially extending groove in the sleeve bearing for preventing the pumping of lubricant from the casing through the space between the shaft and the bearing, the lower end
 45

of said groove communicating with the interior of the casing and the upper end of the groove communicating with the exterior of the casing.

2. In combination, a casing containing lubricant, a sleeve bearing carried by a wall of the casing, a shaft extending through the bearing, means including a reciprocating member within the casing for oscillating the shaft, and an axially extending groove in said bearing for preventing the pumping of lubricant from the casing
 5 through the space between the shaft and the bearing, the lower end of said groove communicating with the interior of the casing and the upper end of the groove communicating with the exterior of the casing.

3. In combination, a casing containing lubricant, a sleeve bearing carried by a wall of the casing, a shaft extending through the bearing, means including a reciprocating member within the casing for oscillating the shaft, axially extending grooves in said bearing arranged in line with the reciprocal movement of said member, and axially extending grooves in said bearing arranged intermediate said first grooves, the lower ends of said grooves communicating with
 20 the interior of the casing and the upper ends of the grooves communicating with the exterior of the casing.

4. In combination, bearing surfaces comprising a sleeve bearing and a shaft extending through the bearing, means for effecting oscillation of the shaft and bearing relative to each other, and an axially extending groove in one of the bearing surfaces for relieving the pressure of the lubricant between the shaft and the bearing whereby
 30 pumping of the lubricant through the space between the shaft and the bearing is prevented.

5. In combination, a stationary bearing surface, a member bearing on said surface, means for reciprocating said member relative to said surface, the reciprocal movement being accompanied by movement of said member toward and away from said surface, and a groove in the said surface extending transversely to the reciprocal movement for relieving the pressure of lubricant whereby pumping of lubricant between the said member and said surface in the direction of said groove is prevented.

45 WILLIAM S. LOWE.
